Patented Mar. 18, 1919.

UNITED STATES PATENT OFFICE.

GEORGE W. GERLACH, OF CUMBERLAND, IOWA.

CIRCUIT-BREAKER.

1,297,343.

Specification of Letters Patent. Patented Mar. 18, 1919.

Original application filed May 26, 1917. Serial No. 171,217. Divided and this application filed December 31, 1917. Serial No. 209,668.

To all whom it may concern:

Be it known that I, GEORGE W. GERLACH, a citizen of the United States, residing at Cumberland, in the county of Cass and State of Iowa, have invented certain new and useful Improvements in Circuit-Breakers, of which the following is a specification.

This invention relates to an improved track obstacle operated circuit breaker, being a division of my pending application for locomotive equipment for block signal systems, filed May 26, 1917, Serial No. 171,217.

The invention has as its primary object to provide a circuit breaker adapted to normally close a circuit with an electrically controlled brake valve actuating mechanism so that when the circuit breaker is engaged by a track obstacle, the circuit will be opened to cause actuation of the said mechanism for moving the brake valve to service position.

The invention has as a further object to provide a circuit breaker adapted to be operated by a track obstacle regardless of the direction in which the train is moving.

And a still further object of the invention is to provide a circuit breaker having the contacts thereof so arranged that loss of any of the movable parts or breaking of any such parts will cause an opening of the circuit controlled by the device.

Other and incidental objects will appear as the description proceeds. In the drawings wherein I have illustrated the preferred embodiment of the invention, and wherein similar reference characters designate corresponding parts throughout the several views:

Figure 1 is a fragmentary perspective view showing a portion of a conventional type of locomotive and illustrating the manner in which my improved circuit breaker is mounted thereon,

Fig. 2 is an elevation showing the circuit breaker in connection with the brake valve of the locomotive, the wiring system being shown diagrammatically, and

Fig. 3 is a horizontal sectional view of the circuit breaker.

Referring more particularly to the drawings, I have shown my improved circuit breaker in connection with a conventional type of locomotive 10 having a break valve 11. This valve is equipped with a lever 12 movable to released position in engagement with a stop 13 and to emergency position in engagement with a stop 14. In connection

with this valve I employ a valve operating mechanism including an electric motor 17 of approved type. This motor is provided with an armature shaft 18 arranged in axial alignment with the stem of the valve and provided at its upper end with a laterally directed arm 19. Connected to the lower end of the armature shaft is a radially extending arm 20 formed at its outer extremity with a downwardly directed terminal 21 adapted to engage the valve lever 12. The motor is so arranged that when energized it will turn the shaft to swing the arm 20 toward the stop 13. Connected to any convenient part of the locomotive cab is a bracket 22 to one extremity of which is pivoted a bell crank 23, one arm of which carries a weight 24 while the other arm of the said bell crank is normally engaged beneath the arm 19 of the motor shaft 18. These parts are so arranged that when the motor is energized and the lever arm 20 is held in engagement with the stop 13, the arm 19 of the motor shaft will hold the bell crank lever in position with the weight 24 elevated. However, upon the deenergization of the motor, the weight will fall and act through the arm 19 to rotate the motor shaft for swinging the lever arm 20 which, in turn, will swing the valve lever 12 to service position. At this time the weighted arm of the bell crank lever will have reached vertical position and further movement of the valve lever will not occur. However, the engineer may move the valve lever on to an emergency position, if deemed advisable.

The improved circuit breaker is supported by a suitable bracket 25 preferably upon the locomotive pilot but may be attached to the bumper timber of the locomotive or other suitable part thereof. A substantially cylindrical casing 26 including a removable face plate 27 is employed. A bracket 28 is fixed within the casing and is formed with an inwardly projecting radial arm 29 to the outer extremity of which is pivoted one end of a relatively strong but resilient contact blade 30 projecting at its free extremity through a suitable slot 31 formed in the peripheral wall of the casing. The blade 30 is, as particularly shown in Fig. 2 of the drawings, preferably tapered from its outer end toward its inner end and the slot 31 is so formed as to allow considerable swing of the blade. Formed on the said blade

immediately outside of the casing are oppositely directed arcuate guard plates 32 which overlie the slot 31 in the normal or central position of the blade and serve to keep dirt, 5 rain, snow, or other foreign matter out of the casing.

Secured to opposite sides of the bracket 28 are reversely bowed resilient contact members 33 and 34 which, at their free ends, 10 engage against opposite sides of the contact blade 30. These spring contacts are insulated from the bracket as shown at 35 and one of the securing screws 36 by which they are fastened to the bracket is, in each instance, so arranged as to serve as an adjusting means for governing the pressure which the respective contacts will exert against the switch blade. As particularly illustrated in Fig. 3 of the drawings, the spring contacts 20 are of somewhat different lengths in order that they may not engage directly opposite portions of the switch blade and each of the said contacts carries an adjustable stop screw 37 engageable by a stud or stop 38 upstanding from the casing. These studs are formed of insulating material. The stop screws 37 are so adjusted that in normal closed position of the circuit breaker they are spaced apart somewhat from the studs 38 but will 30 engage said studs if the switch blade 30 should fall from its place and will, therefore, prevent the spring contacts engaging each other. Furthermore, if the switch blade is swung to one side or the other, 35 springing one of the contacts toward the wall of the casing and permitting the other one to spring in, the stop screw of the latter contact will engage its stop stud and prevent such contact from springing on into 40 engagement with the switch blade. Because of this swinging of the switch blade in either direction, the said blade will act to open a circuit between the spring contacts 34 and 35, which circuit is normally closed by the 45 switch blade.

Binding posts 39 are in electrical connection with the spring contacts 33 and 34 and receive wires 40 and 41, one of which leads to one of the binding posts of the motor 17 50 and the other of which leads to a suitable source of electrical energy such as a battery 42. Connecting the battery with the other binding post of the motor is a wire 43. It will, therefore, be clear that as long as the 55 circuit breaker is in closed or normal position, as shown in full lines in Fig. 3 of the drawings, the motor 17 will be energized and the brake valve will be in released position, although it may be at any time moved 60 to service or emergency position by the engineer. As soon, however, as the switch blade is swung to one side or the other through the engagement therewith of a track obstacle, the circuit through the motor will 65 be broken and the weighted bell crank lever

will turn the armature shaft to move the valve lever to service position. Any approved track obstacle may be employed in connection with the circuit breaker. However, the circuit breaker of the present invention is particularly adapted for operation through engagement with a track obstacle of a type similar to that disclosed in a patent granted to me January 9, 1917, and numbered 1,211,697.

Attention is now directed to the fact that should either of the spring contacts 33 or 34 become broken, the circuit through the motor 17 would be opened when the lever of the brake valve would be immediately moved to service position. In like manner, should either of the said contacts become loosened to fall away from the bracket 28, a similar result would follow. Furthermore, a like result would, as previously intimated, 85 ensue should the blade 30 fall from place. In this connection it will be noted that when the device is mounted upon the locomotive pilot, the contact 33 will be at the rear side of the blade. Therefore, when the locomotive is moved in a forward direction and the blade is engaged by a track obstacle, the greatest stress tending to break the blade will occur at the free end of the said contact. Consequently, should the impact of the track 95 obstacle against the blade be sufficient to actually break the blade, the said blade will, under ordinary conditions, break at a point opposite the free end of the contact 33 when the broken off outer extremity of the blade 100 will fall away to break the circuit between the said contact and the contact 34. A further advantage is thus gained in offsetting the free ends of the contacts with respect to each other since it will be seen that by 105 mounting the circuit breaker with the shorter contact at the rear of the blade 30, the said blade will not be likely to snap off at a point such as would not result in the breaking of the circuit between the contacts. Since a 110 locomotive is seldom run in a backward direction and then only at a relatively low speed, breaking of the blade 30 when the locomotive is so run backwardly will not occur.

It will, therefore, be seen that I have provided a particularly simple and efficient form of circuit breaker for the purpose set forth and a device wherein the development of mechanical trouble within the circuit breaker will cause immediate opening of the brake valve to effect the application of the brakes to the train.

Having thus described the invention, what is claimed as new is:

1. A circuit breaker including a pair of resilient contacts having opposed free ends constantly urged toward each other, and a switch blade pivoted for swinging movement in a plane with the free ends of said con-

tacts and normally engaged thereby to complete a circuit between the contacts.

2. A trip operated circuit breaker including a pair of resilient contacts having opposed free ends constantly urged toward each other, a switch blade pivoted for swinging movement in a plane with the free ends of said contacts and normally engaged thereby to complete a circuit between the contacts, and means for limiting the movement of the free ends of the contacts toward each other.

3. A trip operated circuit breaker including a pair of resilient contacts having opposed free ends constantly urged toward each other, a switch blade pivoted for swinging movement in a plane with the free ends of said contacts and normally engaged thereby to complete a circuit between the contacts, and means for limiting the movement of the free ends of the contacts toward each other, the free ends of the contacts being out of alignment with each other.

4. A trip operated circuit breaker including a pair of resilient contacts having opposed free ends constantly urged toward each other, and a switch blade pivoted for swinging movement in a plane with the free ends of said contacts and normally engaged at spaced points by the ends thereof to complete a circuit between the contacts, the contact engaging the blade nearest its pivot point being disposed at the side of the blade opposite to that normally engaged by a trip.

5. A circuit breaker including a pair of resilient contacts having opposed free ends constantly urged toward each other, means for tensioning the said contacts, and a switch blade pivoted for swinging movement in a plane with the free ends of said contacts

and normally engaged thereby to complete a circuit between the contacts.

6. A circuit breaker including a pivoted switch blade, and resilient contacts mounted to coöperate with the blade and acting thereon to yieldably return the blade when pivoted to centered position closing a circuit between the contacts. 45

7. A circuit breaker including a pivoted switch blade, and resilient contacts mounted to coöperate with the blade in the plane of its pivotal movement and having the blade normally closing a circuit therebetween. 50

8. A circuit breaker including a pivoted switch blade, and opposed resilient contacts mounted to coöperate with the blade and having the blade normally closing a circuit therebetween, the blade being movable for selectively flexing either of said contacts to break a circuit between said contacts. 55

9. A circuit breaker including a pivoted switch blade, and opposed resilient contacts engaging opposite sides of the blade in a plane therewith and acting to normally hold the blade centered closing a circuit between the contacts. 60

10. A circuit breaker including a housing having a slot formed therethrough, a switch blade pivoted within the housing and projecting through said slot, opposed resilient contacts within the housing and coöperating with the blade in the plane of its pivotal movement, the said contacts acting to yieldably return the blade when pivoted to centered position closing a circuit between the contacts, and guard members carried by the blade to normally overlie said slot and close the housing for protecting the contacts. 75

In testimony whereof I affix my signature.
GEORGE W. GERLACH. [L.S.]
